UNITED STATES PATENT OFFICE.

ARCHIBALD M. EWART, OF BARBERTON, OHIO, ASSIGNOR OF ONE-HALF TO WILLIAM A. MORTON, OF BARBERTON, OHIO.

SPOUT ATTACHMENT FOR BOTTLES.

1,175,250.

Specification of Letters Patent. Patented Mar. 14, 1916.

Application filed July 12, 1915. Serial No. 39,377.

To all whom it may concern:

Be it known that I, ARCHIBALD M. EWART, a citizen of the United States, residing at Barberton, in the county of Summit and 5 State of Ohio, have invented certain new and useful Improvements in Spout Attachments for Bottles; and I do declare the following to be a full, clear, and exact description of the invention, such as will enable 10 others skilled in the art to which it appertains to make and use the same.

This invention relates to spout attachments for bottles.

The object of the invention is to provide 15 a simply constructed and efficient device of this character which may be quickly applied to or removed from a bottle and which is more especially designed for use in connection with milk bottles.

20 Another object is to provide an attachment of this character to be applied to the mouths or necks of bottles of various shapes and sizes, and when so applied will direct the pouring of the liquid from the bottle 25 and serve to catch the drip and prevent it from soiling the neck or side of the bottle and the article on which said bottle may be placed.

With these and other objects in view, the 30 invention consists of certain novel features of construction, and the combination and arrangement of parts as will be more fully described and claimed.

In the accompanying drawings: Figure 1 35 represents a side elevation of a portion of a milk bottle showing this improved spout attachment applied; Fig. 2 is a horizontal section taken on the line 2—2 of Fig. 1; and Fig. 3 is a transverse section taken on the 40 line 3—3 of Fig. 2.

In the embodiment illustrated, this improved detachable spout is shown applied to a milk bottle B although obviously it may be applied to the mouth or neck of any other 45 bottle to which it is adapted.

The spout constituting this invention comprises a crescent-shaped plate 1 which may be constructed of any suitable material, such as celluloid, sheet metal, or the like, and is 50 inclined downwardly and inwardly from its outer toward its inner edge as is shown clearly in Fig. 3. The outer edge of this plate 1 is turned inwardly, being preferably rolled to provide a housing 2 which is 55 designed to receive a reinforcing and sup-

porting member 3 here shown in the form of a U-shaped spring wire, the intermediate portion of which conforms to the shape of the outer edge of the plate 1 and is incased in the housing 2 thereof with its free ends 60 projecting beyond the ends of the plate and in longitudinal alinement therewith, and providing resilient clamping arms for engaging the opposite sides of a bottle neck for reliably securing the spout in engagement therewith. These arms are provided at their terminals with loops or eyes 4 to facilitate the clamping engagement and retention of the attachment with the bottle neck and prevent them from injuring the 70 hands of the user or any object with which they may come in contact.

In the use of this improved attachment, the resilient clamping arms of the U-shaped member 3 are sprung into engagement with 75 the opposite sides of a bottle neck adjacent the bead B' thereof with the edge of the plate 1 disposed in contact with said bead and forming a substantially liquid-tight engagement therewith, said plate being inclined downwardly and inwardly toward the bottle as shown in Fig. 3 to form a drip catch as well as to facilitate the pouring of the contents of the bottle.

From the above description, it will be 85 obvious that this attachment while simply constructed, may be quickly and readily applied to a bottle neck and is easily removed for cleaning or other purposes.

I claim as my invention:

1. A detachable bottle spout comprising a crescent-shaped plate having a reinforcing member extending around the outer edge thereof and provided at its ends with resilient clamping arms.

2. A detachable bottle spout comprising a crescent-shaped plate having a resilient clamping arm extending longitudinally from each end thereof, said arms being arranged parallel with each other and adapted 100 to clampingly engage opposite sides of a bottle neck.

3. A detachable bottle spout comprising a crescent-shaped plate having a U-shaped member secured to the one edge thereof with 105 its legs projecting beyond the ends of said plate and in longitudinal alinement therewith.

4. A detachable bottle spout comprising a crescent-shaped plate having its outer edge 110

turned inward to form a housing, and a U-shaped reinforcing wire inclosed in said housing and having its ends projecting beyond the ends of said plate and provided on 10 their terminals with loops.

5. A detachable bottle spout comprising a crescent-shaped plate having its outer edge turned inward to form a housing, and a U-shaped reinforcing wire inclosed in said housing and having its ends projecting be-

In testimony whereof I have hereunto set my hand in presence of two subscribing witnesses.

ARCHIBALD M. EWART.
